Patented Apr. 24, 1973

226,775

BROILER PAN

Robert A. Jones, Louisville, Ky., assignor to
Anaconda Aluminum Company

Filed June 10, 1971, Ser. No. 152,014

Term of patent 14 years

Int. Cl. D7—02

U.S. CL. D44—1 J

FIG. 1

FIG. 2

FIG. 3

FIG. 4

FIG. 5

FIG. 6

FIG. 7

FIG. 1 is a top perspective view of a broiler pan showing my new design;

FIG. 2 is a top plan view of the broiler pan;

FIG. 3 is an end view of the broiler pan;

FIG. 4 is a bottom plan view of the broiler pan;

FIG. 5 is a side view of the broiler pan;

FIG. 6 is a longitudinal section taken substantially along the line 6-6 of FIG. 2; and

FIG. 7 is a cross section taken substantially along the line 7-7 of FIG. 2.

I claim:

The ornamental design for a broiler pan, as shown.
